UNITED STATES PATENT OFFICE.

FRANK CIESZKOWSKI, OF ROBYVILLE, OHIO.

ADJUSTABLE CLOSURE FOR BOTTLES.

1,277,857.

Specification of Letters Patent.

Patented Sept. 3, 1918.

Application filed February 25, 1918. Serial No. 219,024.

To all whom it may concern:

Be it known that I, FRANK CIESZKOWSKI, a citizen of Russia, residing at Robyville, in the county of Harrison and State of Ohio, have invented certain new and useful Improvements in Adjustable Closures for Bottles, of which the following is a specification.

This invention relates to certain new and 10 useful improvements in adjustable closures for bottles.

The primary object of the invention is to provide a closure or stopper for bottles adjustably arranged attached to the bottle 15 whereby the same may be readily opened and closed and temporarily maintained at any adjusted position desired, the device being easy and inexpensive to manufacture and adapted for attachment to any form of bot- 20 tle.

A further object of the invention is the provision of a holder for the cork or closure of a container such as a milk bottle whereby the cork will be retained upon the bottle so 25 as not to become lost and may be readily adjusted into and out of its closing position when desired.

A still further object of the invention is the provision of a cork or closure arranged 30 for ready attachment upon the neck of any form of bottle whereby the closure may be readily positioned for closing the bottle and withdrawn at will, the cork being retained in any of its abjusted positions and being 35 so as not to obstruct the outgoing fluid from the bottle when positioned in its open ar- rangement.

In the drawing forming a part of this application and in which like designating 40 characters refer to corresponding parts throughout the several views,

Figure 1 is an elevational view of a portion of a bottle neck with my device ar- 45 ranged thereon, parts being shown in sec- tion.

Fig. 2 is a view similar to Fig. 1 with the closure positioned in its open arrangement and illustrated by dotted lines in readiness for insertion in the mouth of the bottle.

50 Fig. 3 is a top plan view of the device closed.

Fig. 4 is a view similar to Fig. 1 taken from another side of the bottle neck.

55 Fig. 5 is a further elevational view of a portion of the bottle neck showing the manner of attaching the device thereon.

Fig. 6 is a transverse sectional view taken upon line VI—VI of Fig. 5, and

Fig. 7 is a perspective view of the attaching means for the device removed from the 60 bottle.

While my invention is designed for em- 65 ployment with any form of bottle, the same is herein illustrated in connection with a bot- tle neck 10 having a projecting top bead 11 forming the mouth of the bottle while a cork 12 of substantially the usual form is arranged to be positioned in and withdrawn from the bottle mouth.

A split ring or attaching band 13 formed 70 of resilient material is provided having a loop 14 projecting from one side thereof through the central passage 15 of which a rod 16 is journaled for slidable movement as well as rotation. A reduced tongue 17 is 75 arranged upon one free end 18 of the band 13, at a point substantially opposite the loop 14. The band 13 is adapted for encir- 80 cling the neck 10 in substantial contact with the bead 11 while the tongue 17 is then threaded through a perforation 19 in the opposite free end 20 of the said band and is then bent backwardly upon itself and forced through a struck up eye 21 upon the said end 18 while the tongue may be thereafter 85 bent in the direction toward the end 20 as best illustrated in Fig. 6 of the drawing.

By the arrangement of the band 13 it will be evident that the band may be secured 90 upon bottle necks of different diameters, the band being firmly mounted upon the neck thereof for maintaining the rod 16 positioned substantially parallel with the adja- 95 cent side of the neck. The upper end of the rod 16 is provided with an angular extension 95 or portion 22 secured as at 23 to the top of the cork 12, it being apparent that the cork may be revolved around the main portion of the rod 16 for positioning the cork over the bead 11 for ready insertion in the mouth of 100 the bottle by imparting a downward sliding movement to the rod 16 through the loop 14.

A wheel 24 is arranged at the free end of the rod 16 having a rubber tire or periph- 105 eral band 25 in constant engagement with the bottle neck 10. With the cork 12 ar- ranged in the mouth of the bottle as indicated in Fig. 1 of the drawing, the same may be withdrawn by pushing upwardly upon the wheel 24 and the rod 16 and the 110 contact of the tire 25 with the neck 10 will maintain the cork 12 at any adjusted posi-

2
tion, while the cork may be swung outwardly out of alignment with the neck 10 to the position indicated in Fig. 2 of the drawing and the wheel 24 will then maintain the cork in its open arrangement.

From this detailed description of the invention it will be seen that the cork 12 may be moved as found desirable for closing and opening the mouth of the bottle neck 10, 10 while the wheel 24 by the engagement of the tire 25 with the neck 10 will maintain the cork at any adjusted arrangement. The cork 12 may be readily withdrawn from the mouth of the bottle and turned to a position 15 so as to be out of the way of the outflowing fluid when the bottle is being emptied and may be readily returned to its entering position and reinserted to its closing arrangement in the mouth of the bottle.

20 What I claim as new is:—

1. In combination with the neck of a bottle having a mouth at one end, a band removably secured surrounding the said neck, a projecting loop upon one side of the band, 25 a rod slidably arranged through the said loop positioned substantially parallel with

the adjacent side of the bottle and adapted for revolution, a closure upon one end of the rod adapted for movement inwardly and outwardly of the mouth of the bottle, 30 the said closure being adapted for positioning laterally of the bottle upon a partial rotation of the said rod in the loop, a rubber tired wheel upon the other end of the rod normally contacting the adjacent side of the bottle and adapted for maintaining the said closure and rod in its adjusted relation during the operation of the device.

2. In combination with a bottle neck, a split band mounted upon said neck, a journaling loop upon the band laterally projecting from the bottle neck, a rod journaled in said loop adapted for sliding movement therethrough, a wheel carried by the rod frictionally engaging the adjacent side of 45 the bottle adapted for maintaining the rod in its adjusted position, and a closure member rigidly carried by said rod adapted for seating within the mouth of the bottle when the said wheel is in its lowered position.

In testimony whereof I affix my signature.
FRANK CIESZKOWSKI.
